US00D846593S

(12) United States Design Patent (10) Patent No.: US D846,593 S
Anzures et al. (45) Date of Patent: * Apr. 23, 2019

(54) DISPLAY SCREEN OR PORTION THEREOF WITH ICON(71) Applicant: Apple Inc., Cupertino, CA (US)(72) Inventors: Freddy Anzures, San Francisco, CA (US); Greg Apodaca, Mountain View, CA (US); Ismael Basso, San Francisco, CA (US); Imran Chaudhri, San Francisco, CA (US); Jonathan P. Ive, San Francisco, CA (US); Matthew Dean Rohrbach, San Francisco, CA (US); Wan Si Wan, Sunnyvale, CA (US); Christopher Wilson, San Francisco, CA (US)(73) Assignee: Apple Inc., Cupertino, CA (US)() Term: 15 Years(21) Appl. No.: 29/549,718(22) Filed: Dec. 28, 2015*Related U.S. Application Data

(63) Continuation of application No. 29/473,530, filed on Nov. 22, 2013, now Pat. No. Des. 746,849.

(51) LOC (11) Cl. ..... 14-04(52) U.S. Cl.USPC ..... D14/489(58) Field of Classification Search

CLAIM

The ornamental design for a display screen or portion thereof with icon, as shown and described.

DESCRIPTION

The sole FIGURE is a front view of a display screen or portion thereof with icon showing the claimed design. The broken lines in the FIGURE show a display screen or portion thereof, and form no part of the claimed design.
